UNITED STATES PATENT OFFICE.

GEORGE T. PEARSONS, OF NEW YORK, N. Y.

FIRE-EXTINGUISHER.

1,364,952.

Specification of Letters Patent. Patented Jan. 11, 1921.

Application filed April 1, 1916. Serial No. 88,190.

To all whom it may concern:

Be it known that I, GEORGE T. PEARSONS, a citizen of the United States, residing in the borough of Manhattan, in the city, 5 county, and State of New York, have invented new and useful Improvements in Fire-Extinguishers, of which the following is a specification.

This invention relates to fire extinguishers 10 of the type in which a fire extinguishing liquid is ejected from a reservoir by the pressure of a gas, such gas being the reaction of the mixing of gas generating materials normally held in a separated condition in a generator in the reservoir, and it is the primary object of the invention to provide a fire extinguisher of this type which is in the nature of an automatic unit sprinkler apparatus adapted to be removably 15 supported in an opening in a ceiling or suspended from a suitable support, and automatically set in operation when the surrounding temperature attains a predetermined degree.

20 A further object of the invention is to provide a fire extinguisher of this type in which a generator is employed in which the gas generating materials are maintained in a separated condition when the generator 25 is held in one or an upright position and the materials are adapted to mix when the generator is held in another or inverted position.

It is another object of the invention to 30 provide an extinguisher in which the generator is pivotally supported and retained in an upright position in the reservoir by releasable means controlled by fusible means, the fusing of the fusible means controlling the discharge of the liquid from 35 the reservoir and releasing the generator to permit it to assume an inverted position with the consequent mixing of the materials and generating of gas to forcibly eject the 40 liquid from the reservoir.

A further object is to provide means whereby a portion of the generated gas will be discharged with the liquid from the reservoir, the discharge of such gas with the 45 liquid atomizing or causing the fire extinguishing liquid to be discharged in a very fine spray.

In the drawings accompanying and forming 50 a part of this specification Figure 1 is a sectional side elevation of a fire extinguisher showing an embodiment of my invention,

the parts being shown in full lines in normal position and in dotted lines the position they will assume upon the fusing of the fusible means. 60

Fig. 2 is an enlarged sectional side elevation illustrating a modification of the discharging means.

Fig. 3 is a sectional side elevation illustrating an enlarged view of an embodiment 65 of my invention with the means for discharging a portion of the gas with the liquid from the reservoir; and

Fig. 4 is an enlarged detail view of the 70 fusible closure for the reservoir opening.

The embodiment of my invention shown in the drawing consists of a reservoir 4 of suitable material to contain a fire extinguishing liquid which will volatilize at a heat above ordinary atmospheric temperature, 75 say about 160 degrees, such as carbon tetrachlorid, said reservoir having an opening in the top closed by a removable cover 4'. The reservoir has laterally projecting lugs 5 adjacent the top and bottom adapted to be 80 passed through recesses in an inwardly extending flange 6 of a supporting member 7 secured in an opening in a ceiling and engage with said flange to support the extinguisher. Should it be desired to suspend 85 the extinguisher from a ceiling or the like the lugs at the top are caused to engage with said supporting flange 6 and should it be desired to have the bottom of the extinguisher substantially flush with the ceiling the sup- 90 porting member 7 is secured in line with an opening in the ceiling and the extinguisher is passed through said opening and the lugs adjacent the bottom of the extinguisher caused to engage with the supporting 95 flange 6.

The reservoir has an opening in the bottom in which is fixed a tube 8 extending into the reservoir to adjacent the top with the lower end preferably extending for a short 100 distance out from the reservoir. Slidably supported in the tube 8 is a tube 9 of less diameter and longer than the tube 8, the inner end of said tube having a tubular enlargement 10 with lateral ports 11 communicating with the tube and said enlargement or head where it is connected to the tube being beveled or cone-shaped, as at 12, to cooperate with a correspondingly shaped seat 13 in the top of the tube 8. The tube 9 is in 105 the nature of a carrier for a sprinkler head 14 preferably of cone shape carried and

fixed by a stem 15 to the tube so that it will lie adjacent the end of the tube, and the end of the tube is preferably inclined or beveled inward to correspond with the bevel of the 5 cone portion of the head, as shown at 16. The outer end of the tube 8 is closed by a cover or cap of fusible material 17 inclosing the sprinkler head and preventing the 10 accumulation of foreign substances on the head with the possible clogging and corrosion of said head.

The tubes 8 and 9 have communication with the interior of the reservoir through a tube 18 through which said tubes extend 15 and spaced from the tube 8, the said tube 18 being closed and supported at its lower end, as at 19, and open at its upper end, with a lateral port 20 at its lower end adjacent the bottom of the reservoir closed by an inwardly opening and outwardly closing check 20 valve 21. The carrier tube 9 for the sprinkler head carries at its inner end a further tube 22 closed at the end where it is connected to said carrier 9, the said tube embracing the tube 18 and extending to adjacent the bottom of the reservoir.

Pivottally supported within the reservoir is a receptacle G, which is in the nature of a gas generator, having an outlet 23 leading 30 into the reservoir with a spring influenced check valve 24 opening outward from and closing into the generator. In the present instance the generator is carried in a cage 25 rotatably supported by a laterally projecting shaft 26, fixed thereto journaled in a bracket 28.

As stated this generator is of a type in which gas generating materials, such as bicarbonate of soda and sulfuric or hydrochloric acid, are normally held in a separated condition when the generator is in an upright position and are adapted to come in contact and mix when the generator is inverted. The receptacle G has an open top 40 closed by a removable cover 29. To hold gas generating materials in a separated condition in the receptacle G in the normal position thereof there is provided a receptacle 30 open at one end and of less width than the receptacle G to provide a space between the two receptacles and held in spaced relation by lugs 31 extending laterally from the receptacle 30 engaging with the walls of the receptacle G. The receptacle 30 is supported 45 upon an annular shoulder or ring 32 fixed within the receptacle G at some distance from the bottom, the engagement of the receptacle with this ring separating the lower portion of the receptacle from the upper portion providing a chamber 33 in said receptacle below the receptacle 30 for a purpose to be hereinafter described.

A third receptacle 34 adapted to carry one of the gas generating materials, such as 55 sulfuric or hydrochloric acid, engages in

the receptacle 30 and in the normal position of the generator is supported upon the bottom of said receptacle. This receptacle 34 may be of a size as to width the same as the receptacle 30, but is of less height to leave 70 a space in the receptacle 30 above said receptacle 34, as clearly shown in Fig. 1. The top of the receptacle 34 is closed but is at all times in communication with the receptacle G by tubes 35 extending to the top or beyond 75 the top of the receptacle 30. By this construction the receptacle 30 is adapted to carry the other gas generating material, such as bicarbonate of soda, above the receptacle 34 and separated from the material in said 80 latter receptacle. It will be obvious that when the generator is inverted the soda will drop against the cover 29 which will in said position be the bottom, and the acid in the receptacle 34 will drip through the tubes 35 85 onto the soda and admix therewith generating gas. The receptacle 34 is maintained in position adjacent the bottom of the receptacle 30 when inverted by a rod 36 fixed to the cover extending to a point adjacent 90 the receptacle 34. However, the rod is of such length so that when the generator is inverted the receptacle will move slightly away from the supporting flange 32 connecting the upper and lower parts of the 95 generating chamber and permitting the generated gas to pass between the walls of the receptacles into the chamber 33 and through said chamber out through the outlet 23.

The fire extinguishing liquid is of such a nature that it will not injure articles with which it comes in contact, such as wearing apparel, furniture, carpets and the like. However, the nature of the gas generating 105 materials is such that articles with which it may come in contact will be destroyed and ruined, and it very often happens that portions of said materials are carried off with the generated gas into the reservoir and 110 expelled with the fire extinguishing liquid with the above deleterious results. To prevent this contingency means is provided to render the generated gas anhydrous or dry and non-acid by filtering the generated gas. 115 For this purpose I provide a material through which the generated gas passes to absorb any moisture in such gas, sodium carbonate having been found to answer the purpose. This absorbing material is located in the chamber 33 and normally separated from the upper portion of the receptacle G by the engagement of the receptacle 30 with its supporting flange 32. To prevent this material from dropping into the reacting 120 materials when the generator is inverted there is provided a fine mesh screen 37 removably secured to the flange 32. To prevent the generated gas from expelling any 125

of the filtering material through the outlet 23 there is connected to the outlet a tube 38 to extend into the chamber 33, said tube having lateral ports 39 with a fine mesh screen 40 extending around said ports. The generator is maintained in its normal position by releasable latching means, shown as consisting of a bolt 41 carried by the generator carrying cage 25 to engage with a bifurcated end of a lug 22' extending laterally from the closure for the top of the tube 22 when said tube is maintained in its raised position by the fusible means through the tube 9.

15 In charging the extinguisher the discharging tube is adjusted so that the bolt 41 will engage with the bifurcated lug 22' when the fusible cover 17 is applied to retain the parts in such position, when the charged 20 generator is placed into the top of its carrying cage 25 and retained therein by a releasable closure 42 for said opening, after which the reservoir is supplied with the fire extinguishing liquid and the cover 4' applied 25 thereto when the extinguisher is placed in its support 7 and supported therein by the lugs 5.

In operation when a fire occurs and the atmosphere reaches a predetermined temperature above the ordinary atmospheric 30 temperature the fusible means will be fused or melted releasing the discharge tube 9 carrying the sprinkler head permitting it to drop through the open end of the tube 8 35 until the cone portion 12 engages with the seat 13. The tube 22 being connected to the tube 9 will drop with it away from the bolt 41 when the generator will swing with its cage to assume an inverted position, as 40 shown in dotted lines in Fig. 1, it being understood that the generator carrying cage is so supported that the cage with the generator will tend to assume such position by gravity when the bolt 41 is released by the 45 tube lug 22'. As the generator assumes this position the soda will drop against the cover 29, then the bottom of the generator and the receptacle 34 will drop away from the screen 37 until it engages with the end of 50 the rod 36, and the acid will drip from the receptacle 34, through tubes 35 onto said soda immediately generating gas, the generated gas passing through the space between the receptacles 30 and G, through the filtering 55 material into the outlet tube 38 and through the outlet 23 into the reservoir where the expansive force of such gas on the liquid in the reservoir will expel the liquid through the port 20 into tube 18 and 60 up through said tube through the ports 11 of the tubular enlargement of the tube 9 and out through said latter tube, the sprinkler head diffusing said liquid laterally in all directions as it passes out from the tube 9.

65 It will be obvious that the tube 18 in some

instances could be dispensed with as shown in Fig. 2, in which instance the liquid in the reservoir is forced up the tube 22 and from said tube through the ports 11 into the tube 9.

The fusible closure for the reservoir opening consists of an annular member 43 having screwthreaded connection with the outer end of the tube 8, the said member having an inward extending flange with an opening 70 preferably of slightly greater diameter than the tube 9. This opening is closed by a disk consisting of sections 44 of non-fusible material secured together and retained in the opening in the member 43 by a fusible 75 shoulder, as shown at 45. When a fire occurs and the surrounding atmosphere reaches a predetermined temperature the fusible solder holding the sections together and said sections in the opening in the member 43 will be melted and the sections drop from the opening. To prevent any possibility of said fused material coming in contact with the sprinkler head connected to the tube 9 there is provided a disk 46 of non-fusible metal on the inner side of the sections 44, as clearly shown in Fig. 4, such disk being of such diameter as to permit it to readily pass through the opening in the member 43.

As stated it is an object of the invention to discharge a portion of the generated gas from the reservoir to atomize or discharge the liquid from the reservoir in a fine spray. For this purpose, as shown in Fig. 3, a 100 tube 47 having a restricted opening therethrough is carried by the discharge tube to extend therethrough with its lower end adjacent the lower end of the discharge tube and its upper end communicating with the 105 reservoir, as shown at 48. This tube, as shown, may also serve as the carrier for the head 14 to connect the head to the discharge tube, as at 49. The tube 47 has lateral ports 50 adjacent the head 14 whereby as the liquid from the reservoir is forcibly ejected through the discharge tube from the reservoir a very fine jet or jets of gas will be impinged upon said discharging liquid just above the sprinkler head thereby breaking 110 up the discharging liquid into small particles with the consequent result that the liquid will be discharged in a fine spray.

Having thus described my invention I claim:

1. In a fire extinguisher, the combination of a reservoir for a fire extinguishing liquid having an outlet; fusible means to seal said outlet; a gas generator in said reservoir having means to hold gas generating materials 125 in a separated condition therein when the generator is held in one position and to permit said materials to mix when the generator is held in another position; and means held in position by the fusible means to co- 130

operate with the generator to maintain it in position with the materials therein in a separated condition, the fusing of said fusible means permitting said means to release the 5 generator to assume a position so that the materials therein will mix, substantially as and for the purpose specified.

2. In a fire extinguisher, the combination of a reservoir for a fire extinguishing liquid 10 having an outlet; fusible means to seal said outlet; a gas generator having an outlet and means to hold gas generating materials therein in a separated condition when in an upright position and to permit said materials 15 to mix when it is inverted; and means to releasably support the generator in the reservoir in an upright position and adapted to be released to permit the generator to assume an inverted position upon the fusing 20 of the fusible closure for the reservoir outlet, substantially as and for the purpose specified.

3. In a fire extinguisher, the combination of a reservoir for a fire extinguishing liquid 25 having an outlet; fusible means to seal said outlet; a gas generator having an outlet and means to hold gas generating materials therein in a separated condition when in an upright position and permit said materials to 30 mix when it is inverted; means to pivotally support said generator in the reservoir; and releasable means to maintain said generator in an upright position in the reservoir, said means adapted to release the generator and 35 permit it to assume an inverted position upon the fusing of the fusible closure for the reservoir outlet, substantially as and for the purpose specified.

4. In a fire extinguisher, the combination 40 of a reservoir for a fire extinguishing liquid having an outlet; fusible means to seal said outlet; a gas generator having an outlet and means to hold gas generating materials therein in a separated condition when in an 45 upright position and permit said materials to mix when it is inverted; a pivotal support for said generator in the reservoir; and releasable means coöperating with said support to maintain it in position with the generator in an upright position, said means adapted to release the generator support to 50 permit the generator to assume an inverted position upon the fusing of the fusible closure for the reservoir outlet, substantially as and for the purpose specified.

5. In a fire extinguisher, the combination 55 of a reservoir for a fire extinguishing liquid having an outlet; fusible means to seal said outlet; a gas generator having an outlet and 60 means to hold gas generating materials therein in a separated condition when in an upright position and permit said materials to mix when it is inverted; a carrier for said generator; means to pivotally support said carrier in the reservoir; releasable

means to coöperate with said carrier to maintain it in position with the generator in an upright position; and means operable upon the fusing of the fusible closure for the reservoir outlet to release said means and 65 permit the carrier to assume a position with the generator in an inverted position, substantially as and for the purpose specified.

6. In a fire extinguisher, the combination 70 of a reservoir for a fire extinguishing liquid having an outlet; fusible means to seal said outlet; a gas generator having an outlet and means to hold gas generating materials therein in a separated condition when in an upright position and permit said materials 75 to mix when it is inverted; a cage to carry said generator having a laterally projecting shaft to pivotally support the cage in the reservoir; and means held in position by the fusible closure for the reservoir outlet to co-operate with means carried by the cage to maintain the cage in position with the generator in an upright position, said means being adapted to release the cage upon the fusing of the fusible closure for the reservoir outlet and permit the cage to assume a 80 position with the generator in an inverted position, substantially as and for the purpose specified.

7. In a fire extinguisher, the combination 85 of a reservoir for a fire extinguishing liquid arranged to be supported in fixed position and having an opening adapted to be sealed by fusible means; a pivotally supported gas generator in the reservoir having an outlet 90 leading into the reservoir and having means to hold gas generating materials in a separated condition when in upright position and permit said materials to mix when inverted; and a tube through which to discharge the liquid from the reservoir normally positioned within the reservoir and shut off from the exterior of the reservoir by the fusible means and said tube arranged 95 to coöperate with the generator to maintain the generator in upright position when positioned within the reservoir, the fusing of said fusible means permitting said tube to be projected from and discharge the liquid exterior of the reservoir and by such movement releasing the generator to permit it to assume an inverted position, substantially as and for the purpose specified.

8. In a fire extinguisher, the combination 100 of a reservoir for a fire extinguishing liquid having an opening; fusible means to seal said opening; a generator in the reservoir having an outlet leading into the reservoir, said generator adapted to hold gas generating materials in a separated condition when 105 in an upright position and permit said materials to mix when it is inverted; an outlet tube for the reservoir engaging in the opening therein and shut off from the exterior 110 of the reservoir by the fusible means, said 115

5 tube coöperating with the generator when in such position to maintain the generator in an upright position, and the fusing of the fusible means opening said tube to the exterior of the reservoir and causing the tube to release the generator to permit it to assume an inverted position, substantially as and for the purpose specified.

9. In a fire extinguisher, the combination 10 of a reservoir for a fire extinguishing liquid having an opening therein; fusible means to close said opening; a generator in the reservoir having an outlet leading into the reservoir, said generator adapted to hold 15 gas generating materials in a separated condition when in an upright position and permit said materials to mix when it is inverted; means to pivotally support the generator in the reservoir; an outlet tube for the 20 reservoir slidably engaging in the opening therein, said tube being shut off from the exterior of the reservoir by the fusible means and maintained in position to co-operate with means carried by the support 25 for the generator to maintain said support in position with the generator in an upright position, the fusing of said fusible means opening said tube to the exterior of the reservoir and causing the tube to release the 30 generator support to permit the generator to assume an inverted position, substantially as and for the purpose specified.

10. In a fire extinguisher, the combination 35 of a reservoir for a fire extinguishing liquid; a tube extending from the bottom to adjacent the top of the reservoir with the lower end opening to the outside of the reservoir; fusible means to close said end of the tube opening to the outside of the reservoir; and 40 a liquid discharge tube for the reservoir extending through the first tube, said tube being shut off from the exterior of the reservoir by the fusible means for the first tube, and the fusing of said fusible means opening 45 said second tube to the exterior of the reservoir, substantially as and for the purpose specified.

11. In a fire extinguisher, the combination 50 of a reservoir for a fire extinguishing liquid having an opening in the bottom; a tube fixed in said opening extending adjacent the top of the reservoir; fusible means to close the lower end of said tube; a generator in which to generate gas in the reservoir having 55 an outlet leading into the reservoir; and a tube through which to discharge the liquid from the reservoir extending through the first tube, the fusible means also shutting off said tube from the exterior of the reservoir, 60 and the fusing of said fusible means opening said tube to the exterior of the reservoir, substantially as and for the purpose specified.

12. In a fire extinguisher, the combination 65 of a reservoir for a fire extinguishing liquid

having an opening in the bottom; a tube fixed in said opening extending to adjacent the top of the reservoir; fusible means to close the lower end of said tube; a tube through which to discharge the liquid from the reservoir 70 extending through the first tube and communicating at the upper end with the interior of the reservoir, the lower end being shut off from the exterior of the reservoir by the fusible means, and the fusing of the 75 fusible means opening said tube to the exterior of the reservoir; and a head secured to and spaced from the lower end of the tube, substantially as and for the purpose specified.

13. In a fire extinguisher, the combination 80 of a reservoir for a fire extinguishing liquid having an opening in the bottom; a tube fixed in said opening to extend to adjacent the top of the reservoir; fusible means to close the lower end of said tube; a generator in which to generate gas within the reservoir having an outlet leading into the reservoir; a tube through which to discharge the liquid from the reservoir 85 engaging in the first tube, said fusible means also shutting off said tube from the exterior of the reservoir; means to connect the inner end of the second tube with the reservoir; and a sprinkler head carried at the lower end of 90 the second tube, substantially as and for the purpose specified.

14. In a fire extinguisher, the combination 95 of a reservoir for a fire extinguishing liquid having an opening therein; a generator in 100 which to generate gas within the reservoir having an outlet leading into the reservoir; a tube fixed in the opening in the reservoir extending to adjacent the top of the reservoir; fusible means to close the outer end of said tube; a second tube engaging in the first tube connected at its inner end with the interior of the reservoir and through which to discharge the liquid from the reservoir, said 105 fusible means shutting off said tube from the exterior of the reservoir; and a head carried at the outer end of said latter tube, substantially as and for the purpose specified.

15. In a fire extinguisher, the combination 110 of a reservoir for a fire extinguishing liquid having an opening therein; a generator to generate gas within the reservoir having an outlet leading into the reservoir; a tube fixed in the opening in the reservoir to extend to adjacent the top of the reservoir; fusible 115 means to close the other end of the tube; a second tube slidably engaging in the first tube with its inner end extending from the first tube through which to discharge the liquid from the reservoir, said fusible means 120 shutting off said second tube from the exterior of the reservoir; a head carried at the outer end of said second tube; and means to connect the inner end of said tube with the liquid in the reservoir adjacent the bottom 125 130

thereof, substantially as and for the purpose specified.

16. In a fire extinguisher, the combination of a reservoir for a fire extinguishing liquid having an opening therein; a generator to generate gas within the reservoir having an outlet leading into the reservoir; a tube fixed in the opening in the reservoir to extend to adjacent the top of the reservoir; fusible means to close the other end of the tube; a second tube slidably engaging in the first tube with its inner end extending from the first tube through which to discharge the liquid from the reservoir, said fusible means shutting off said second tube from the exterior of the reservoir; a head carried at the outer end of said second tube; and a third tube to connect the inner end of the second tube with the liquid in the reservoir adjacent the bottom, substantially as and for the purpose specified.

17. In a fire extinguisher, the combination of a reservoir for a fire extinguishing liquid having an opening therein; a generator to generate gas within the reservoir having an outlet leading into the reservoir; a tube fixed in the opening in the reservoir to extend to adjacent the top of the reservoir; fusible means to close the other end of the tube; a second tube slidably engaging in the first tube with its inner end extending from the first tube through which to discharge the liquid from the reservoir, said fusible means shutting off said second tube from the exterior of the reservoir; a head carried at the outer end of said second tube; a third tube extending from the bottom of the reservoir to adjacent the inner end of the discharge tube and connected at its lower end with the reservoir; and a tube carried by the discharge tube to embrace the third tube, substantially as and for the purpose specified.

18. In a fire extinguisher, the combination of a reservoir for a fire extinguishing liquid having an opening therein; a generator in the reservoir having an outlet leading into the reservoir, said generator adapted to hold gas generating materials in a separated condition when in an upright position and permitting said materials to mix when in an inverted position; a carrier to pivotally support the generator in the reservoir; a tube fixed in the opening in the reservoir extending to adjacent the top of the reservoir; fusible means to close the outer end of said tube; a second tube engaging in the first tube through which to discharge the liquid from the reservoir, said fusible means shutting off said tube from the exterior of the reservoir; a head connected to the outer end of said second tube; means to connect the inner end of the second tube with the liquid in the reservoir adjacent the bottom; and means carried by the second tube to coöperate with means

connected to the carrier for the generator to maintain the generator in an upright position, the fusing of the fusible means connecting said second tube with the exterior of the reservoir and releasing the carrier for the generator to permit it with the generator to assume an inverted position, substantially as and for the purpose specified.

19. In fire extinguishing apparatus, the combination of a reservoir for a fire extinguishing liquid having an outlet, said reservoir adapted to be removably connected to a fixed support; fusible means to close said outlet; a pivotally supported gas generator having an outlet leading into the reservoir and means to hold gas generating materials therein in a separated condition when in an upright position and to permit said materials to mix when the generator is inverted; and means to releasably maintain the generator in an upright position and adapted to be released to permit the generator to assume an inverted position upon the fusing of the fusible closure for the reservoir, substantially as and for the purpose specified.

20. In fire extinguishing apparatus, the combination of a reservoir for a fire extinguishing liquid having an outlet; fusible means to close said outlet; a pivotally supported gas generator having an outlet leading into the reservoir and means to hold gas generating materials therein in a separated condition when in an upright position and to permit said materials to mix when the generator is inverted, and having means through which the generated gas is passed before it enters the reservoir to filter said gas; and means to releasably maintain the generator in an upright position, said means adapted to release the generator to permit it to assume an inverted position upon the fusing of the fusible closure for the reservoir, substantially as and for the purpose specified.

21. In a fire extinguisher, the combination of a reservoir for a fire extinguishing liquid having an opening in the bottom; a gas generator in said reservoir; a liquid discharge tube supported in the reservoir in line with the opening in the reservoir to extend into the reservoir to adjacent the top; fusible means to close said tube; and means connected to said tube to permit a portion of the gas generated in the reservoir to be discharged with the liquid, substantially as and for the purpose specified.

22. In a fire extinguisher, the combination of a reservoir for a fire extinguishing liquid having an outlet; a gas generator in said reservoir to hold gas generating materials and the reactive mixture free from the liquid in the reservoir and having an outlet leading into the reservoir; means connected to the outlet of the reservoir to per-

mit a portion of the generated gas to be expelled with the liquid; and fusible means to close the reservoir outlet, substantially as and for the purpose specified.

23. In a fire extinguisher, the combination of a reservoir for a fire extinguishing liquid having an outlet; a generator in said reservoir to normally hold gas generating materials in a separated condition; an outlet leading from the generator into the reservoir having an outwardly opening and inwardly closing spring influenced valve; means to filter the generated gas before it is utilized to expel the liquid from the reservoir; means connected to the reservoir outlet to permit a portion of the gas to be expelled from the reservoir with the liquid; and fusible means to close the reservoir outlet, substantially as and for the purpose specified.

24. In a fire extinguisher, the combination of a reservoir for a fire extinguishing liquid having an opening; fusible means to close said opening; a generator to normally hold gas generating materials in a separated condition having an outlet leading into the reservoir; means operable upon the fusing of the fusible means to cause the materials to mix in the generator; and a tube to cause a portion of the gas to be expelled with the liquid from the reservoir, substantially as and for the purpose specified.

25. In a fire extinguisher, the combination of a reservoir for a fire extinguishing liquid having an opening; fusible means to close said opening; a generator to hold gas generating materials in a separated condition when in upright position and permit said materials to mix when inverted and having an outlet leading into the reservoir; a liquid discharge tube for the reservoir connected with the opening therein to extend adjacent the top of the reservoir and connected with the liquid in the lowermost part of the reservoir, said tube being shut off from the exterior of the reservoir by the fusible closure for the reservoir opening, and the fusing of said fusible means connecting said tube with the exterior of the reservoir, and said tube and generator having means to coöperate to maintain the generator in upright position when the reservoir opening is closed by the fusible means and adapted to release the generator to permit it to assume an inverted position upon the fusing of the fusible means; and a tube extending through the discharge tube having an outlet adjacent the outlet of the discharge tube and connected with the reservoir adjacent the top to discharge a portion of the gas with the liquid from the reservoir, substantially as and for the purpose specified.

26. In a fire extinguisher, the combination of a reservoir for a fire extinguishing

liquid having an opening; fusible means to close said opening; a generator to normally hold gas generating materials in a separated condition when in upright position and adapted to mix when inverted and having an outlet leading into the reservoir; a liquid discharge tube for the reservoir connected with the opening therein to extend adjacent the top of the reservoir and shut off from the exterior of the reservoir by the fusible means and having means to maintain the generator in upright position; a head connected to the discharge end of said tube; means to connect the upper end of said tube with the liquid in the lowermost part of the reservoir; the fusing of the fusible means opening said discharge tube to the exterior of the reservoir and releasing the generator to permit it to assume an inverted position; and a tube extending through the discharge tube having an outlet adjacent the head connected to the discharge tube and connected with the reservoir adjacent the top to discharge a portion of the gas with the liquid from the reservoir, substantially as and for the purpose specified.

27. In a fire extinguisher, the combination of a reservoir for a fire extinguishing liquid having an opening; a fusible closure for said opening; a pivotally supported generator in said reservoir adapted to hold gas generating materials in a separated condition when in an upright position and cause said materials to mix when inverted; a liquid discharge tube for the reservoir communicating at its lower end with the opening in the reservoir and extending to adjacent the top of the reservoir, said tube shut off from the exterior of the reservoir by the fusible closure and coöperating with means connected to the generator to maintain it in an upright position; a sprinkler head connected to the lower end of said tube; means to connect the upper end of the tube with the liquid in the lowermost part of the reservoir; the fusing of the fusible means opening the discharge tube to the exterior of the reservoir and causing said tube to release the generator to permit it to assume an inverted position and the gas generating materials to mix; and a tube extending through the discharge tube having an outlet at one end adjacent the sprinkler head and the other end communicating with the reservoir to discharge a portion of the gas with the liquid from the reservoir, substantially as and for the purpose specified.

28. In a fire extinguisher, the combination of a reservoir having an opening in the bottom; a fusible closure for said opening; a tube secured in said opening extending into the reservoir; a gas generator to create pressure in the reservoir and having an outlet leading into the reservoir; a second tube ex-

tending through the first tube to have longitudinal movement and through which to discharge the liquid from the reservoir and normally positioned within the first tube 5 by the fusible closure, said tube having means to coöperate with the first tube to seal the same from the gas in the reservoir and connect the discharge tube with the liquid in the lower part of the reservoir, substantially as and for the purpose specified.

29. In a fire extinguisher, the combination of a reservoir for fire extinguishing liquid having an opening therein; a fusible closure for said opening; a gas generator in 15 the reservoir arranged to carry gas generating materials in a separated condition when in upright position and to mix when the generator is inverted; a tube through which to discharge the liquid from the 20 reservoir normally positioned within the reservoir by the fusible closure and having means to coöperate with the generator to retain it in upright position, said tube upon the fusing of the fusible closure being projected from the opening in the reservoir to 25 discharge the liquid exterior of the reservoir and release the generator for the purpose specified.

30. In a fire extinguisher, the combina-

tion of a reservoir for fire extinguishing liquid and having an opening; a fusible closure for said opening; a pivotally supported gas generator in said reservoir having an outlet leading into the reservoir and arranged to hold gas generating materials 35 in a separated condition when in upright position and permit said materials to mix and generate gas when inverted; and a tube through which to discharge the liquid from the reservoir normally positioned within 40 the reservoir and shut off from the exterior of the reservoir by the fusible closure, and said tube arranged when positioned in the reservoir to coöperate with the generator to maintain the generator in upright position, 45 the fusing of said fusible closure permitting said tube to be projected from the reservoir and discharge the liquid to the exterior thereof, and by said movement releasing the generator to permit the generator to assume an inverted position and generate gas, and said discharge tube also being arranged to discharge a portion of the generated gas therethrough from the reservoir, substantially as and for the purpose 50 specified.
